Application August 1, 1942, Serial No. 107,787

Term of patent 3½ years

To all whom it may concern:

Be it known that I, Aaron Dexter Johnson, a citizen of the United States of America, residing at Rochester, in the county of Monroe and State of New York, have invented a new, original, and ornamental Design for Photo Albums, of which the following is a specification, reference being had to the accompanying drawing, forming a part thereof in which:

Figure 1 is an inside view of the photo album with the foldable parts thereof arranged in a flat

or fully-opened relation, showing my new design, the backs of the cover being plain.

Figure 2 is a perspective view of Fig. 1, but with one of the foldable parts moved to a position normal to the other part to partly close the album.

I claim:

The ornamental design for a photo album, as shown and described.

AARON DEXTER JOHNSON.
